UNITED STATES PATENT OFFICE.

CHARLES HERRMAN, OF NEW YORK, N. Y., ASSIGNOR TO UNDERWOOD TYPEWRITER COMPANY, OF NEW YORK, N. Y., A CORPORATION OF DELAWARE.

TYPEWRITING MACHINE.

Application filed March 31, 1922. Serial No. 548,282.

To all whom it may concern:

Be it known that I, CHARLES HERRMAN, a citizen of the United States, residing in New York, in the county of New York and State of New York, have invented certain new and useful Improvements in Typewriting Machines, of which the following is a specification.

The present invention relates to rolls for holding work-sheets to the platen of a typewriting machine. More particularly, the invention relates to rolls of this class, which are usually associated with, or form part of, resilient, marginal paper-fingers or clips for guiding the work-sheets across the printing line, and for holding the sheets flat on the platen at and just beyond the printing line; such fingers or clips being usually adjustable lengthwise of the platen according to the width of the sheet, card or envelope to be held thereby.

For a clean-cut, uniform impression of the type, it is important that there be no bulging or crumpling of the paper at the printing line; the paper should be flat and smooth on the platen where the printing is done. The stock being printed on may, however, be so stiff as to have a tendency to bulge, or it may be so light as to crumple readily; thus causing trouble and uncertainty in the attainment of the desired flat and smooth setting of the work-sheet on the platen.

An object of the present invention is the provision of means for causing the rolls of the clips to draw laterally outward on the margins of the work-sheets to flatten the latter against the platen at the printing line.

A further object of the invention is the provision of means whereby the lateral pull or strain of the rolls on the work-sheets may be regulated to the particular stock being written on. The lateral pull required to flatten a heavy card might, for instance, tear or distort a sheet of light or flimsy material. Hence, the desirability of such regulating means.

In the preferred embodiment of the invention, hereinafter described in detail, the rolls are caused to draw laterally on the paper by having their axes of rotation set obliquely to the direction of feed of the paper, instead of, as heretofore, parallel to the axis of the platen; and the desired adjustment of the lateral pull of the rolls on the paper is effected by changing the angle of

the rolls to the platen; the lateral pull being nil when the rolls are parallel to the platen, and increasing in strength as the angle of the rolls to the platen is increased.

Features of the invention are the provision of simple and effective means for swinging and locking the rolls; of means for determining the parallel position of the rolls with respect to the platen and preventing an accidental angular setting thereof which would cause the paper to be crowded or crumpled, instead of flattened, between the same; and of means for determining the extreme angle beyond which the rolls cannot be swung without causing them to drag on the paper.

A feature of the present invention is the provision of means whereby the rolls may have a play to and from the platen independently of, or with respect to, the paper-fingers; so that the rolls may have the desired resiliency and certainty of action regardless of stiffness, or even of injury, of the paper-fingers; and vice versa, so that the paper-fingers may be of any required strength without regard to the resiliency required by the rolls.

A feature of the invention is the provision of means for quickly, accurately, and detachably securing the rolls to the paper-fingers, and for securing both of these parts to supporting brackets; not only for purposes of assembly, but so that an injured or worn paper-finger or roll may be replaced without discarding the other of such parts.

Other features and advantages will hereinafter appear.

In the accompanying drawings,

Figure 1 is a view in front elevation, showing a rotary platen and a frame therefor, and showing the paper-fingers of the present invention in operative position with respect to the platen.

Figure 2 is a view in side elevation, taken on the line 2-2 of Figure 1.

Figure 3 is an enlarged detail view showing in plan the mounting of the roll on the left-hand paper-finger.

Figure 4 is a view in cross-section on the line 4-4 of Figure 3.

Referring to the drawings, the platen-frame consists of side-pieces 10 connected by rods 11 and 12, and having revolvably mounted thereon a platen 13. The usual lower rear and front feed-rolls 14 and 15, respectively, are indicated in dotted lines

in Figure 2. As indicated by the type-bar 16, shown in dotted lines in Figure 2, the machine is a front-strike machine.

The paper-fingers 26 are carried by arms 5 or brackets 17, supported on the rod 11. In the drawings, the bracket 17 is shown in the position in which it holds the paper-finger in operative, paper-engaging position. The paper-fingers are, however, ordinarily adapted 10 to be thrown up, and away from the platen, to an inoperative position, and, for this purpose, the arms or brackets 17 are pivotally connected to the rod 11. For holding the brackets 17 in effective position, the rod 11 is splined at 18, and a lateral shelf 15 or extension 19 carries a leaf-spring, not shown, which, in turn, carries a key, indicated at 20 in Figure 2, for engagement with the spline in the rod 11. When the bracket 20 is turned to the Figure 2 position, the key 20 registers with the spline 18; and the leaf-spring, not shown, causes the key to enter the spline and lock the bracket in its normal position. When the arm or bracket 17 is 25 thrown up to remove the paper-fingers from the platen, the leaf-spring, referred to, permits the key 20 to be forced out of the spline-way 18, but it causes the key thereafter to bear upon the rod 11 in such manner 30 as to hold the bracket against accidental displacement, with the paper-fingers in inoperative position. For throwing the bracket up and down with the paper-finger, the bracket has at its forward end a finger-piece 21. The 35 connections of the bracket 17 to the rod 11, just described, are those found on the Underwood standard typewriting machine, and so are not more specifically illustrated.

For supporting the paper-finger on its 40 respective bracket, the latter, at its forward end, has a laterally-offset arm or plate 24. Each paper-finger 26 is curved in general 45 conformity to the curvature of the platen, but, at its upper end, has a flat offset portion 27 which is adapted to be set against the back of the bracket-plate 24. The paper-finger is held to the bracket-plate 24 by 50 means of screws 30, which pass through the paper-finger and through the plate 24, and which thread into a block or plate 31 behind the paper-finger.

As shown in Figures 1 and 3, the paper-fingers 26 have lateral offsets 32. Mounted 55 to swing on a screw or pin 33, as a pivot, there is on each paper-finger, a finger or arm 34 carrying a roll 35. The roll 35 has its shaft 36 revolvably mounted in ears 37 which are shown as stamped and turned upward out of the material of the finger 34. Each paper-finger has an arcuate slot 38 60 struck from the pivot-point 33 as a center, through which slot the roll 35 is adapted to engage the platen. Behind the pivot 33, each of the fingers 34 has an extension which is slotted at 39 also on an arc struck from the

70 pivot 33 as a center. Threaded into a boss 40 on the paper-finger, and extending through the slot 39 in the roll-carrying finger, is a thumb-screw 41, by means of which the roll-carrying finger 34 may be locked in any angular position or adjustment to which it may have been turned on its pivot 33. The pivot-pin or screw 33 is also preferably threaded into a boss 42 carried by the 75 paper-finger; the bosses 40 and 42 being of the same height and having finished faces on which the roll-carrying arm moves.

Two stop-pins 43 and 44, carried by the 80 paper-finger 26, limit the throw of the roll-carrying finger. When the roll-carrying finger 34 abuts the stop 43, the axis 36 of the roll 35 is parallel to the axis 45 of the platen, and no lateral tensioning or pull on the paper is effected by the rolls. With the roll-carrying fingers 34 in any position 85 between the stops 43 and 44, other than the position shown in Figure 3, the rolls exert a lateral outward pull on the paper, which tends to flatten the same against the platen; and the farther the roll-carrying fingers 34 90 are swung toward the stop 44, the stronger and more effective is this lateral pull. If the roll-carrying fingers 34 were swung below the position defined by the stop 43, the tendency of the rolls would be to push the 95 paper toward one another and crumple the same, which would be undesirable. The stops 43, therefore, serve to prevent any such accidental defective setting of the rolls. The stops 44 prevent the rolls from riding up 100 onto the fingers and out of contact with the platen beyond the rear ends of the arcuate slots.

The angular position of the roll-carrying 105 arms will be determined by the weight, quality, width and other characteristics of the stock of which the sheets are made. A lateral pull, sufficient or desirable to hold a sheet of heavy stock flat against the platen, might, for instance, tear a lighter or more 110 flimsy piece of paper. The desired setting of the fingers 34 may, however, be readily determined in any particular instance.

The paper-finger 26 and the roll-carrying 115 finger 34 are both shown as of sheet-metal, and will ordinarily be of resilient sheet-metal having a set which tends to cause the rolls to bear with the proper pressure upon the platen.

Ordinarily where the rolls are mounted 120 directly upon the paper-fingers, the resiliency of the latter is relied upon for the proper pressure of the rolls upon the platen. If the stock of the paper-fingers is sufficiently light and flexible to provide 125 this resiliency, the fingers may easily be bent or otherwise injured, so as to be defective in their function as paper-guides. Where, however, as in the present case, the rolls are not directly supported upon the 130

paper-fingers, but are supported upon arms which are yieldable with respect to the paper-fingers, the paper-fingers may be comparatively stiff and strong, and the 5 arms upon which the rolls are directly supported may be looked to for the resiliency required of the rolls. In the structure shown in the drawings, the paper-fingers 26 may be of heavier or thicker sheet-metal than 10 the arms 34; the thickness of the arms 34 and the spring set of the same being such as to result in a delicate spring action of the rolls on the platen or paper.

The paper-fingers 26 are of a curvature 15 which conforms in general to the curvature of the platen. On the other hand, the path of movement of the roll-carrying arms 34, more especially at the pivot-pins 33, is somewhat tangential to the surfaces of the 20 supporting paper-fingers. If, therefore, the arms 34 moved in a simple plane when swung rearward on their pivots, the rolls might leave the platen or the pressure of the same on the platen be undesirably relieved. If, however, the roll-carrying arms 25 34 be of the proper shape and flexibility and have the proper spring set, they will follow the curvature of the paper-fingers and will cause the rolls to continue to bear 30 with the proper pressure upon the platen when swung rearward. The flat, thin, spring-metal arms 34, held to the paper-fingers as indicated in the drawings, will exert a proper pressure of the rolls on the 35 platen in any angular position to which the rolls may be swung.

Variations may be resorted to within the scope of the invention, and portions of the improvements may be used without others.

Having thus described my invention, I claim:

1. In a typewriting machine, a rotary platen, marginal paper-fingers for guiding the paper around the platen, one at each 45 side of the paper, an adjustably mounted roll connected to each finger for holding the paper to the platen, and means for setting the axes of the rolls obliquely to the path of movement of the paper to cause the rolls to draw laterally on the paper.

2. In a typewriting machine, a platen adapted to have line-space movement, a roll for holding paper to the platen, and adjustable means for setting the roll obliquely to the path of movement of the paper to cause the roll to draw laterally thereon.

3. In a typewriting machine, in combination with a platen adapted to have line-space movement, a pressure roll adapted to ride 60 on the platen, and a carrier for the roll angularly adjustable therewith to cause the roll to draw laterally on paper being fed over the platen.

4. In a typewriting machine, in combination with a platen adapted to have line-

space movement, a pressure roll adapted to ride on the platen, a carrier for the roll angularly adjustable therewith to cause the roll to draw laterally on paper being fed over the platen, a paper-guiding finger on 70 which the roll-carrier is pivoted, and stops on the finger for limiting the angular throw of the roll-carrier.

5. In a typewriting machine, in combination with a platen adapted to have line-space movement, a pressure roll adapted to ride on the platen, a carrier for the roll angularly adjustable therewith to cause the roll to draw laterally on paper being fed over the platen, a paper-guiding finger on 75 which the roll-carrier is pivoted, and means for determining a position of the roll-carrier in which the roll will not draw laterally on the paper.

6. In a typewriting machine, in combination with a platen adapted to have line-space movement, a pressure roll adapted to ride on the platen, a carrier for the roll angularly adjustable therewith to cause the roll to draw laterally on paper being fed 80 over the platen, a paper-guiding finger on which the roll-carrier is pivoted, and means on the paper-finger for locking the roll-carrier in adjusted position.

7. In a typewriting machine, in combination with a platen adapted to have line-space movement, a pressure roll adapted to ride on the platen, a carrier for the roll angularly adjustable therewith to cause the roll to draw laterally on paper being fed 85 over the platen, a paper-guiding finger on which the roll-carrier is pivoted, and a screw on the paper-finger operating through a slot in the roll-carrier for locking the latter in adjusted position.

8. In a typewriting machine, in combination with a platen adapted to have line-space movement, a pressure roll adapted to ride on the platen, and an arm on which the roll is mounted; the arm being angularly adjustable with the roll to cause the latter to draw laterally on paper being fed over the platen, and being of spring metal to cause the roll to bear resiliently on the platen.

9. In a typewriting machine, in combination with a platen adapted to have line-space movement, a pressure roll adapted to ride on the platen, an arm on which the roll is mounted; the arm being angularly adjustable with the roll to cause the latter to draw laterally on paper being fed over the platen, and being of spring metal to cause the roll to bear resiliently on the platen, and a resilient sheet-metal paper-guiding finger on which the roll-carrying arm is pivoted.

10. In a typewriting machine, a rotary platen, a finger curved in general conformity with the curvature of the platen for guid-

4

ing paper across the printing line, an arm pivoted to the paper-guiding finger in such manner that it may be swung forward and rearward angularly over the platen, and a roll carried by said arm to ride on the platen; the arm being of a material and shape such that in all positions thereof it will cause the roll to bear resiliently on the platen.

- 10 11. In a typewriting machine, the combination with a cylindrical platen, of feed-rolls engaging the side margins of a work-
sheet in the machine and operated by the advance of the platen, said feed-rolls being
15 constructed and mounted to have the portions of their peripheries in engagement with the work to travel outward when so operated to rub outward the side margins

of the work-sheet, and so to spread and
smooth the work-sheet.

- 20 12. In a typewriting machine, the combination with a cylindrical platen, of cylindrical feed-rolls running upon and rotated by the platen to engage the opposite side margins of a work-sheet in the machine, said feed-rolls being mounted with their axes inclined upwardly and inwardly, the feed-rolls when rotated by the advance of the platen drawing obliquely outward upon the work-sheet and spreading and smooth-
25 ing it.

CHARLES HERRMAN.
